PAGE 2

Fig. 4

Fig. 5

Fig. 6

FIGURE 1 is a top plan view of a convertiplane embodying our new design;

FIGURE 2 is a front elevational view thereof;

FIGURE 3 is a side elevational view thereof;

FIGURE 4 is a top plan view thereof with the wing in position for hovering and vertical flight;

FIGURE 5 is a front elevational view thereof in the position as shown in FIGURE 4;

FIGURE 6 is a side elevational view thereof in the position as shown in FIGURE 4; and

FIGURE 7 is a rear perspective view thereof in the position as shown in FIGURE 4.

We claim:

The ornamental design for a convertiplane, substantially as shown and described.
